UNITED STATES PATENT OFFICE

1,950,869

CENTRIFUGAL

Joseph Stuart, 2d, Wilmington, Del., assignor to
Hercules Powder Company, Wilmington, Del.,
a corporation of Delaware

Application June 8, 1931, Serial No. 542,820

6 Claims. (Cl. 210—63)

This invention relates to a centrifugal and particularly to a centrifugal of self-cleaning type adapted to handle materials continuously.

The ordinary used type of centrifugal is adapted only for batch operation since in the case of ordinary materials which it handles these materials tend to pile up on the perforated walls and remain there. The permanence of adhesion is particularly noticeable in the cases of materials such as nitrocotton which are generally treated centrifugally for removal of the nitrating acids.

It is the broad object of the present invention to provide a self-cleaning centrifugal which by reason of its self-cleaning action is adapted for a continuous treatment of substances to effect the separation of liquid and solid portions thereof.

Briefly, the centrifugal comprises a cylinder formed by a helical portion of a continuous wire. During the rotary action the wire progresses from one end to the other of this helix thereby effecting a constant change of relation between the various portions of the helix to effect the separation of the solid material adhering thereto.

Other objects of the invention relating particularly to the details of construction will become apparent from the following description read in conjunction with the accompanying drawings in which:

Fig. 1 is a plan view partly in section of one form of the device;

Fig. 2 is an elevation of the same also partly in section;

Fig. 3 is a diagrammatic sectional view illustrating the path through which the flexible wire moves; and

Fig. 4 is a sectional detail showing the mounting of the wire to form the necessary helix.

The device is supported from a base conventionally illustrated at 2 and includes a frame 4 carried by the base which forms a suitable mounting for certain moving elements. The frame 4 forms a part of the liquid receiving casing 6, the frame and the casing being formed of proper materials which will not be corroded in case the centrifugal is being used for the separation of acids or other corrosive materials from solid substances. A discharge portion is formed by a flange 8 which as will be clear hereafter extends in close proximity with the lower end of the helix.

Mounted in suitable bearings in the frame 4 are upright spindles 10 carrying pulleys 12 about which a belt 14 may be trained so that all of the spindles 10 are simultaneously rotated. The intermediate portions of the spindles 10 take the

form of drums 16 provided with annular grooves 18 within which lie the convolutions 20 of a continuous wire or rod, or the like, of suitable material and dimensions.

At any instant the wire forms distinct portions, one of which is the helix 20, the convolutions of which are guided within the grooves 18 in the drums 16. It may be pointed out that the grooves in the drums 16 are separate and circular and not helical although the various convolutions of the wire 20 do form a helix, the proper maintenance of this helix being effected by longitudinal displacement of the grooves in the successive drums. From the top of the helix the wire extends outwardly as indicated at 22 while at the bottom of the helix it likewise extends outwardly as indicated at 24. A loop 26 is thereby formed extending about a guide disc 28, the wire being maintained in a groove in this disc by suitable small grooved pulleys 30 and being properly guided where it extends away from the disc by grooved pulleys 32. A suitable passageway 34 is provided where the wire passes outwardly through the casing 6 so that any acid carried by the wire will be entrapped. Discharge of liquid from the casing 6 takes place as indicated at 36. Material is charged into the helix through a suitable conduit 38 and is carried away from the helix by a further suitable conduit or chute 40. In order to properly distribute the incoming material about the walls of the helix there is provided a disc 42 carrying upright vanes 44 the disc being supported by a spindle 46 suitably mounted in the frame and driven through the medium of a belt trained about a pulley 48.

In the operation of the device the mixed solid and liquid material passes through the inlet conduit 38 upon the rapidly rotating disc 42 from which it is thrown by the action of vanes 44 against the helix formed by the wire 20. At this time by reason of the rotation of the spindles 10 the wire moves in the direction of the arrow, passing into the helix at 22 and threading downwardly to where it passes outwardly as indicated at 24. This rotation is preferably of the order of 1500 to 2500 R. P. M., averaging about 2000 R. P. M. and by reason of this rapid rotation the liquid is drawn outwardly into the casing 6 whereas the solid material remains in contact with the convolutions of the wire, the spacing between which is suitably small so that an openwork basket is provided. The pitch of the helix which defines the size of the openings may of course be of any suitable degree to provide the proper openings which will pass the liquid but retain the solid portions of the mate-

rial being handled. At the bottom of the helix the solid material is released by reason of the departure of the wire from the cylindrical contour previously followed. The solid materials which are still moving rapidly will then engage the inner portions of the flange 8 and be thereby guided downwardly to the discharge 40.

It will be seen from the above that the centrifugal is self-cleaning and capable of effecting continuous operation inasmuch as the liquid is removed from the solid portions of the material being treated during the time when the material moves downwardly from the point of inlet to the point of exit.

It is found that by reason of the high speed of rotation the convolutions of the wire are maintained centrifugally in proper engagement with the grooves 18 and that there is required no inner support therefor. Since the disc 28 is arranged so that the wire engages it tangentially at the bottom of the helix and leaves it tangentially at the top thereof, no difficulty is experienced in maintaining the loop 26 under proper control.

What I claim and desire to protect by Letters Patent is:

1. A centrifugal including an endless member arranged to move helically to define by a plurality of convolutions in proximity to each other a rotating basket, means arranged outside of the basket defined for spacing and guiding the convolutions of the member, means for so moving the member arranged outside of the basket defined, and means for introducing material into the basket so defined.

2. A centrifugal including an endless member arranged to move helically to define by a plurality of convolutions in proximity to each other a rotating basket, means arranged outside of the basket defined for spacing and guiding the convolutions of the member, means for so moving the member arranged outside of the basket defined, means for guiding the portion of the mem-

ber extending from one end of the basket to the other, and means for introducing material into the basket so defined.

3. A centrifugal including an endless member arranged to move helically to define by a plurality of convolutions in proximity to each other a rotating basket, means arranged outside the basket defined for spacing and guiding the convolutions of the member, means for so moving the member arranged outside of the basket defined, means for introducing material into the basket so defined and means within the basket defined for throwing the material against the basket walls.

4. A centrifugal including an endless member arranged to move helically to define by a plurality of convolutions in proximity to each other a rotating basket, means arranged outside the basket defined for spacing and guiding the convolutions of the member, means for so moving the member arranged outside the basket defined, means for introducing material into the basket so defined and means within the basket defined for throwing the material centrifugally against the basket walls.

5. A centrifugal including an endless member arranged to move helically to define a rotating basket, driving means positioned outside of the basket defined and arranged to support said endless member in its helical movement, and means for introducing material into the basket defined.

6. A centrifugal adapted for separating a solid from a liquid including an endless member arranged to move helically to define a rotating basket, driving means positioned outside of the basket defined and arranged to support said endless member in its helical movement, means for introducing material into the basket defined, means for collecting a separated liquid and means for collecting and discharging a separated solid.
